(57) **CLAIM**

The ornamental design for a ceiling fan housing with light kit, as shown and described.

DESCRIPTION

FIG. 1 is a perspective view of a ceiling fan housing with light kit, showing the new design;

FIG. 2 is an enlarged perspective view thereof;

FIG. 3 is an enlarged front elevational view thereof;

FIG. 4 is an enlarged rear elevational view thereof;

FIG. 5 is an enlarged left side elevational view thereof;

FIG. 6 is an enlarged right side elevational view thereof;

FIG. 7 is an enlarged top plan view thereof;

FIG. 8 is an enlarged bottom plan view thereof;

FIG. 9 is an enlarged left elevational view of a portion thereof; and,

FIG. 10 is an enlarged bottom plan view of a portion thereof.

The broken lines illustrate portions of the ceiling fan housing with light kit, and also illustrate environmental structure. The broken lines form no part of the claimed design.
